UNITED STATES PATENT OFFICE.

GEORGE BAN McDONELL AND EDWARD LAWRENCE PECK, OF BARTLESVILLE, OKLAHOMA, ASSIGNORS, BY MESNE ASSIGNMENTS, TO DOHERTY RESEARCH COMPANY, OF NEW YORK, N. Y.

BAILER.

1,426,305.

Specification of Letters Patent. Patented Aug. 15, 1922.

Application filed November 16, 1920. Serial No. 424,367.

To all whom it may concern:

Be it known that we, GEORGE B. McDONELL and EDWARD L. PECK, citizens of the United States, residing at Bartlesville, county of Washington, State of Oklahoma, have invented certain new and useful Improvements in Bailers; and we do hereby declare the following to be a full, clear, and exact description of the invention, such as 10 will enable others skilled in the art to which it appertains to make and use the same.

This invention relates to bailers, and more particularly to the type of bailers used in the drilling of petroleum oil wells.

15 When drilling deep wells, the drill bit is usually worked in water to assist in removing the cuttings and the materials set free by the bit. As the drilling proceeds a mud or sludge is formed from the cuttings which 20 is periodically removed from the well by a bailer. The bailer commonly consists of a cylindrical shell having a gravity operated check valve at the lower end arranged to be opened to admit liquid into the bailer when 25 the bailer reaches the bottom of the well, and to trap liquid in the bailer as the bailer is lifted.

While drilling the upper sections of a well, and especially when passing through 30 relatively soft rock formation, regardless of the section of the well in which the formations occur, it is the best drilling practice to use a bailer having a diameter only slightly smaller than the diameter of the well, or the 35 diameter of the casing of the well. Such a bailer assists in keeping a straight vertical hole and prevents formations of the obstructions and irregularities in the side walls of the hole. The full size bailer is 40 also very effective for cleaning the bottom of the well.

It often happens that a well contains 45 large quantities of water and in such a well the bailer is always lowered to the bottom of the well to be filled. When a filled bailer of the full size of the well is being lifted out of the well, there is little opportunity for the water above the bailer to flow to the lower end of the bailer. Accordingly, the 50 bailer acts as a piston to raise a large portion of the water trapped above it, and this condition places a very heavy load on the hoisting machine.

The primary object of the present invention

55 is to provide a bailer by which liquid may be readily conducted from a point above to a point below the bailer, when the bailer is lifted in a body of liquid with its trapping valve closed.

Another object of the invention is to provide a bailer with a liquid bypass which will not be clogged by the mud being handled.

With these and other objects in view, the invention consists in the improved bailer 65 hereinafter described and particularly defined in the claims.

The various features of the invention are 70 illustrated in the accompanying drawings in which;

Fig. 1 is a view in vertical section of a bailer embodying the preferred form of invention.

Fig. 2 is a vertical section of the bailer shown in Fig. 1, the section being taken at 75 right angles to the section shown in Fig. 1, and

Fig. 3 is a horizontal section of the bailer taken on the line 3—3 of Fig. 2.

The bailer illustrated in the drawings 80 consists of a modification of the usual type of bailer, to provide a bypass through the bailer for the flow of the liquid from above to below the bailer at the time a filled bailer is being raised out of a well. The fluid 85 handling portion of the bailer comprises a cylindrical container 10 secured to a shoe 12 and a dart 14 arranged to cooperate with a valve seat 16 in the shoe to trap liquid in the container 10. The construction and arrangement of the parts mentioned above 90 are substantially the same as that embodied in the commonly used bailer, the dart 14 being arranged to close the valve seat 16, while the bailer is being lifted, and to engage the bottom of the well to lift the head 95 of the dart from the valve seat 16 when the bailer reaches the bottom of the well.

To provide a bypass in the bailer so that a bailer of the full size of the well may be 100 used for cleaning a well, an outer shell 18 is positioned around the container 10 with its upper end secured by rivets 20 to the upper end of the container, and its lower end secured to the shoe 12. A lifting bail 105 22 is secured to the upper end of the shell 18.

The outer shell is arranged to have a cross section of substantially the same shape and

area as that of a well in which the bailer is to be used, and has a diameter greater than the diameter of the container 10, to provide a peripheral space 24 between the shell and container. The space 24 forms a bypass passage through which liquid may flow while the bailer is being lifted through a body of liquid at the bottom of a well. Openings 26 are formed in the shoe which lead from the bottom of the passage 24 to a point in the shoe below the valve seat 16. By this construction the liquid above the top of the container 10 will flow through the bypass to the space below the bailer as the bailer is lifted. The lifting volume of the bailer consists of the volume of the liquid trapped in container 10 between its top and the valve seat 16.

The openings 26 are so positioned in the shoe 12 that when the bailer is lowered in the bottom of the well, the mud at the bottom would be forced directly into them. Some forms of the mud or sludge often act to clog these openings so that when the bailer is lifted, the bypass through passages 24 and the openings 26 is closed. To prevent the bypass from being clogged a valve 28 consisting of the frusto-conical disc is positioned below the openings 26 and arranged to engage a conical valve seat 30 formed in the shoe 12. The valve 28 is freely movable between the valve seat 30 and a series of pins 32 which are positioned in the shoe 12 and tend to limit the downward movement of the valve. When the bailer enters liquid at the bottom of a well, the valve 28 will be moved in contact with the seat 30 to close the passages 26 and thus prevent mud from entering the bypass. At the time the bailer is lifted the valve 28 will be forced by gravity into contact with the pins 32 and open the openings 26 so that liquid can flow through the bypass 24-26.

With the construction outlined above a bailer of the full size of the well may be used in drilling without placing a heavy strain on the lifting motor. The construction for trapping the liquid in the bailer is simple and will not get out of order, and

the bypass has no complicated parts to get out of order. It is apparent that the bypass 24-26 would operate effectively if the valve 28 were omitted, but it is preferred to use the valve in order to avoid any liability of the openings 26 becoming clogged.

While the bailer illustrated in the drawings is particularly adapted for use in drilling oil wells, it is obvious that it is not limited to any such use, but may be used for bailing liquid in any type of well or shaft.

The preferred form of the invention having been thus described, what is claimed as new is:

1. A bailer comprising, an outer shell of substantially the same shape and area as the bore of a well in which it is to be used, a lifting attachment at the upper end of the shell, a container of approximately the same length as the shell positioned within said shell to provide a peripheral space between said shell and container, a valve for closing the lower end of said container, and a valve for closing said peripheral space.

2. A bailer comprising, a shell, a valve for closing one end of the shell, a lifting attachment for the shell, a bypass for leading fluid through said shell from above to below the shell when the shell is being lifted, and a valve for closing said bypass while the shell is being lowered into a body of liquid.

3. A bailer comprising, an outer shell, a shoe in the lower end of said shell, a container of approximately the length of the shell positioned within said shell with its lower end secured in said shoe and arranged to provide a peripheral channel between said shell and container, a valve seat formed in the portion of said shoe covered by said container, a check valve for closing said seat, said shoe being provided with passages communicating with said peripheral space and extending to a point below said valve seat, and a valve for closing said passages.

In testimony whereof we affix our signatures.

GEORGE BAN McDONELL.
EDWARD LAWRENCE PECK.
